UNITED STATES PATENT OFFICE.

CHARLES H. CHILDS, OF UTICA, NEW YORK, ASSIGNOR TO THE CHARLES H. CHILDS & COMPANY.

PLANTER.

SPECIFICATION forming part of Letters Patent No. 619,388, dated February 14, 1899.

Application filed December 30, 1898. Serial No. 700,742. (No model.)

To all whom it may concern:

Be it known that I, CHARLES H. CHILDS, a citizen of the United States, residing at Utica, in the county of Oneida and State of New York, have invented certain new and useful Improvements in Planters; and I do hereby declare the following to be a full, clear, and exact description of the invention, such as will enable others skilled in the art to which it applies to make and use the same.

My invention consists in the novel features hereinafter described, reference being had to the accompanying drawings, which illustrate one form in which I have contemplated embodying my invention, and said invention is fully disclosed in the following description and claims.

Referring to the drawings, Figure 1 is a side view, partly in section, of a hand corn-planter embodying my invention, parts being broken away. Fig. 2 is an enlarged sectional view of a portion of my improved feed-plate. Fig. 3 is a vertical central section through the hopper, showing the feed-plate and the means for adjusting the same. Fig. 4 is a detail perspective view of a portion of the bottom of the hopper, the feed-plate, and its adjusting devices, the parts being shown separated to illustrate the construction of each separate part. Fig. 5 is a view looking down upon the feed-plate, the parts of the feed-plate being broken away to show the hopper-bottom and the discharge-orifice therein.

The object of my invention is to provide a movable feed-plate for planters having a series of apertures or pockets in which the capacity of said apertures or pockets may be varied as required for different kinds and different quantities of seeds without changing the horizontal area of the seed-delivering apertures or pockets.

In the drawings I have shown my invention embodied in a hand corn-planter of a well-known type, in which A represents the standard, provided with a handle a, B the spout, b the delivery end, C the operating-arm, and D the foot, all of well-known constructions.

The seed-hopper is preferably constructed in two parts. E represents the hopper-bot-

tom, consisting of a circular bottom plate having an annular flange e and a bracket-arm e', which is bolted or otherwise secured to the standard A. The bottom plate is provided with a delivery-aperture e² of elongated or elliptical form and with a central recess e³, the side wall of which is slotted at e⁴ to receive one end of a reciprocating lever e⁵. The bottom plate is also provided with a central aperture e⁶, and the annular flange e is provided with a slot e⁷, through which a pawl e⁸, carried by the lever e⁵, extends into the hopper and engages the revoluble feed-plate, as hereinafter described. The flange e is also provided with a vertically-extending lug e⁹, to which is secured a brush e¹⁰, preferably by means of a screw, the said brush being located directly above the delivery-aperture e² and engaging the upper face of the revolving feed-plate.

My improved feed-plate is constructed as follows and comprises a circular plate having a series of apertures therein, a second plate parallel therewith provided with a series of apertures corresponding to those of the first plate, said second plate being provided with a flange surrounding each of its said apertures on one side of the plate, the said flanges telescoping into the apertures in the first-mentioned plate, and means for adjusting one of said plates with respect to the other in a direction parallel to the axis of rotation of said plates.

In the construction herein shown, F represents the lower plate, provided with a circular series of apertures f, corresponding in size to the delivery-aperture e² and adapted to register therewith as the plate is revolved. The plate F is provided on its lower side with a hollow sleeve or hub f', the lower end f² of which is reduced in diameter and passes through an aperture e¹¹ in the lever e⁵ and through the central aperture e⁶ in the bottom of the hopper.

G represents the upper plate—in this instance the adjustable plate—provided with a series of apertures g, corresponding with the apertures f of the plate F, and having on its lower face downwardly-extending flanges g', surrounding each of the apertures g, said flanges being constructed to telescope and fit

within the apertures f , as shown in Figs. 2 and 3. The plate G is provided with a central sleeve g^2 , which extends downwardly within the sleeve f' of the plate F and forms 5 a guide for the plate G.

H represents an adjusting-screw, the lower portion of which is threaded and engages a contracted threaded aperture f^3 at the bottom of the sleeve f' . The adjusting-screw H is 10 provided within the sleeve f' with a collar h , rigidly secured thereto and engaging the lower end of the sleeve g^2 of the upper plate, so that by turning the screw H in one direction the said collar will raise the sleeve g^2 15 and plate G, as indicated in dotted lines in Fig. 2. On turning the screw in the opposite direction the collar h will be lowered and will permit the plate G to move downward; but in order to make this a positive movement I 20 prefer to form a lateral projection on the screw H above said plate G, and in this instance I have shown the upper end of said screw provided with a washer h' , above which the screw is headed or riveted, as indicated 25 at h^2 , it being understood that the screw H turns freely within the sleeve g^2 .

It will be apparent that by means of the screw H the plate G can be raised or lowered with respect to the plate F, and the size of 30 the feed-apertures can be varied by increasing or diminishing their depth. By this means I secure the necessary variation in the capacity of the feed-apertures without changing their horizontal area, and thus avoid all 35 danger of clogging, which is almost inevitable where the area of the apertures is changed.

The lower plate F is provided on its periphery with notches f^4 to receive the pawl e^8 , carried by the lever e^5 . This lever is actuated 40 by means of a link c' from the operating-arm C in a well-known way to impart an intermittent movement to the revoluble feed-plate.

In order that the adjustment of the feed-plate may be accomplished entirely by hand 45 and without the use of any tools whatsoever, the screw H is provided with a clamping-nut and with a finger-piece, by means of which it can be turned by hand, the clamping-nut being also provided with means by which it 50 can be operated by the fingers. I prefer to use an ordinary nut h^3 in connection with a clamping-plate h^4 , adapted to engage the lower end of the sleeve f' , said clamping-plate being provided with a square recess h^5 to receive the nut and with wings h^6 , by means of 55 which it can be turned simultaneously with the nut.

h^7 represents a wing-head having a threaded recess which is screwed onto the lower end 60 of the screw H so tightly that the screw can be turned in either direction by means of the wing-head. By this means the operator is enabled to quickly adjust the plate F to vary the capacity of the feed-apertures, using his 65 fingers only, without having recourse to a wrench, screw-driver, or other tool.

E' represents the main body of the hopper,

which is attached to the hopper-bottom by means of screws or otherwise and provided with a removable cover E².

While I have shown my improved feed-plate in this instance applied to a hand-planter, I do not limit myself to its use in such connection, as it can be used with good results in many other forms of planters.

What I claim, and desire to secure by Letters Patent, is—

1. A feed-plate for planters comprising among its members two parallel plates having corresponding apertures forming the seed-delivery apertures and means for adjusting one of said plates toward and from the other to vary the depth of said seed-delivery apertures, substantially as described. 80

2. A feed-plate for planters comprising among its members two parallel plates each provided with corresponding apertures one of said plates being provided with projecting flanges surrounding the apertures thereof and telescoping within the apertures of the other 90 plate, and means for adjusting one of said plates toward and from the other, substantially as described. 85

3. A feed-plate for planters comprising among its members, the lower plate provided with a circular series of apertures, the upper plate having a corresponding series of apertures, and a flange surrounding each aperture on the lower side of said plate, said flanges telescoping into the apertures of the lower plate, and an adjusting-screw operatively connected with said upper plate for adjusting it toward and from the lower plate, substantially as described. 95

4. A feed-plate for planters comprising among its members the lower plate provided with a central sleeve and a circular series of apertures, the upper plate having a central guiding-sleeve fitting within the sleeve of the lower plate, said upper plate having a series 100 of apertures corresponding with those of the lower plate and provided on its lower face with a flange surrounding each aperture, said flanges telescoping into the apertures of the lower plate, and an adjusting device engaging the sleeve of the upper plate up and down to adjust the upper plate with respect to the lower plate, substantially as described. 110

5. In a planter, the combination with a feed-plate comprising among its members two parallel plates provided with corresponding apertures, one of said plates being provided with a flange surrounding each of its apertures, said flanges telescoping within the apertures of the other plate, of an adjusting-screw provided with a hand operating device, for moving one of said plates toward and from the other, and a hand operating locking-nut for said screw, substantially as described. 120

6. A feed-plate for planters comprising among its members the lower plate provided with a central sleeve and a circular series of apertures, the upper plate having a central guiding-sleeve fitting within the sleeve of the 130

lower plate, said upper plate having a series of apertures corresponding with those of the lower plate and provided on its lower face with a flange surrounding each aperture, said

5 flanges telescoping into the apertures of the lower plate, an adjusting-screw operatively connected to the sleeve of the upper plate, a hand operating device for rotating said screw to move the upper plate toward and from the

lower plate, and a hand operating locking-nut for said screw, substantially as described.

In testimony whereof I affix my signature in the presence of two witnesses.

CHARLES H. CHILDS.
